CLAIM

The ornamental design for a handheld portable high fidelity music playback with streaming and WIFI routing, as shown and described.

DESCRIPTION

FIG. 1 is a rear elevational view of a handheld portable high fidelity music playback with streaming and WIFI routing showing the new design;

FIG. 2 is a front elevational view thereof;

FIG. 3 is a left side elevational view thereof, the right side elevational view being a mirror image thereof;

FIG. 4 is a top plan view thereof; and,

FIG. 5 is a bottom plan view thereof.

The broken lines illustrate unclaimed portions and form no part of the claimed design.
